UNITED STATES PATENT OFFICE.

JOHN TIMOTHY HODGES, OF ROCKPORT, INDIANA.

DEVICE FOR TIMING PHOTOGRAPHIC EXPOSURES.

SPECIFICATION forming part of Letters Patent No. 793,932, dated July 4, 1905.

Application filed June 6, 1904. Serial No. 211,381.

To all whom it may concern:

Be it known that I, JOHN TIMOTHY HODGES, a citizen of the United States, residing at Rockport, in the county of Spencer and State of Indiana, have invented a new and useful Device for Timing Photographic Exposures, of which the following is a specification.

It is customary in making photographic exposures to time the latter in accordance with the shadows surrounding and upon the image irrespective of the high lights, and in order that a clear sharp picture may be produced it is imperative that the exposure of the sensitive plate or film be continued until there is reproduced upon the latter any and all details which may exist in the deepest shadows.

My invention has for its objects to produce a comparatively simple inexpensive device by which the requisite time for exposures may be readily and accurately determined to thus produce clear sharp negatives and one which may be effectively employed as a focusing glass or instrument.

To these ends the invention comprises the novel features of construction and combination of parts more fully hereinafter described.

In the accompanying drawings, Figure 1 is a perspective view of a device embodying my invention. Fig. 2 is a vertical longitudinal sectional elevation through the same. Fig. 3 is a detail perspective view of the shaft, timing members, and partitions removed from the casing. Fig. 4 is a view similar to Fig. 1 of the device as seen from the opposite side.

Referring to the drawings, 1 designates the casing as a whole, comprising a pair of end members or heads 2 3 and a tubular shell 4, constituting the outer wall and into which the heads are seated, the parts being maintained in assemblage by means of a central bolt or shaft 5, preferably square or of other non-circular form in cross-section, while the head 2 is provided between its center and margin with an annular internally-threaded opening 6 in axial alignment with a similar but somewhat larger opening 7 formed in the head 3, this latter opening being surrounded by an outwardly-projecting externally-threaded flange 8.

Tapped into the threaded opening 6 is a tubular focusing member or section 9, carrying upon its interior and adjacent to its inner end a biconvex magnifying-lens 10, arranged concentric of an outwardly-flaring conical focusing member or tube 11, tapped onto the externally-threaded flange 8 and of which the tube 9 forms, in effect, a continuation.

Housed within the casing 1 is a plurality of timing members or disks 12 13 14 15, spaced one from another and having interposed therebetween relatively thin division-plates or partitions 16, which are mounted directly upon and prevented from rotation by the non-circular shaft 5, the timing members being, however, rotatable upon suitable bearing sleeves or collars 17, in turn fixed upon and against rotation by the shaft, it being apparent from this arrangement that the disks are free for independent rotation and are prevented from contact one with another by means of the partitions 16, whereby liability of one disk being accidentally rotated through frictional contact with another is wholly obviated. Each partition 16 has formed therein an annular opening 18, the openings in the respective partitions being in axial alignment with one another and with the openings 6 7, while in each of the rotary timing-disks there is formed a pair of annular openings 19 20, preferably arranged as shown in Fig. 3 and of a diameter corresponding to that of the openings 18, in register with which latter either of the openings 19 20 may be brought at will by partial rotation of the disks, which

for this purpose are provided each with a finger piece or pin 21, projecting radially from the periphery of the disk through one of a series of slots or guides 22, provided in the wall 4 of the casing. The guide-slots, which obviously correspond in number to the number of disks, are of such length that when the pins 21 come in contact with and are brought to rest by the opposite ends of the slot one or the other of the openings 19 20 in the disks will be in proper register with the openings 18. Thus the pins and slots constitute means for limiting the rotation of the disks and for determining the registration of the openings. Each of the disks carries

within its opening 20 a translucent sheet or filling 23, of glass or other suitable material, said sheets in the respective disks being of relatively varying degrees of translucency or 5 opacity, proportionately increasing in density from the outermost disk 12 toward the innermost disk 15, the glass 23 of the disk 12 being, for instance, of one degree of density, that of the disk 13 two degrees, of the disk 14 10 four degrees, and of the disk 15 eight degrees.

In practice when it is desired to ascertain the time necessary for an exposure the outer end of tube 11 is placed against the object-glass at the back of the camera immediately 15 over the image reflected thereon, and the disks are manipulated for bringing certain ones or a sufficient number of the translucent sheets 23 into play for neutralizing the lights and shadows in the image until the details of 20 the latter are obscured or, that is, until the illumination of the shadows is practically destroyed, and the number of degrees of opacity as represented by the translucent sheet or sheets thus brought into action permits a 25 ready determination of the time required for the exposure. It is to be noted in this connection that the timing-disks may by bringing them into play singly or in different combinations have a scope of from one to fifteen 30 degrees of density.

Provided upon the wall 4 of the casing is a scale 24, computed in accordance with the degree of opacity of the plates 23 and indicating the length of time necessary for exposures wherein the shadows in the object being photographed are reduced to a loss of detail by the required degree of opacity of the plate or plates, it being apparent from this 35 scale that the length of time required for the exposure gradually increases as the number of degrees of opacity of the sheet or sheets brought into play decreases or, that is, as the strength of the high lights decreases and the depth of the shadows increases.

40 It is apparent from the foregoing that I produce a comparatively simple inexpensive device admirably adapted for readily and accurately timing exposures and one which may by moving the disks to throw their plates 23 out of action and bringing their 45 openings 19 into register be employed as a focusing-glass. In attaining these ends it is to be understood that I do not limit or confine myself to the precise details herein set 50 forth, inasmuch as minor changes therein may be resorted to without departing from the spirit of the invention, it being obvious, among other changes, that the number of 55 disks employed and the degree of translucency of the plates 23 may be varied at will.

Having thus described the invention, what is claimed is—

1. In a device of the class described, a casing subdivided into a plurality of compartments and provided with a sight-opening, a

plurality of movable members inclosed with- 70 in the respective compartments of the cas- ing and having translucent portions adapted to be brought into line with the sight-opening, means for limiting the movement of the members in either direction, and a focusing-lens arranged within said sight-opening.

2. In a device of the class described, a cas- 75 ing having partitions therein forming simi- lar compartments, said casing having a sight- opening alining with openings in the parti- tions, and a plurality of guide-slots, a plu- rality of independently-rotatable members inclosed within the respective compartments of the casing and each having a translucent 80 portion and an opening adapted to be brought, respectively, into line with the sight-opening, and means carried by the members and working, respectively, in the guide-slots for operating said members, said means being 85 adapted to contact with the ends of the slots for limiting the movement of the members in either direction when the openings or translucent portions thereof are in alinement with the sight-opening. 90

3. In a device of the class described, a closed casing having detachable end walls and provided with a sight-opening, a shaft 95 extending through the casing and engaging the end walls thereof, stationary partitions carried by the shaft and each provided with an opening in alinement with the sight-opening, a plurality of movable members rotatably mounted on the shaft between the parti- 100 tions and having translucent portions adapt- ed to be brought into line with the sight-opening, and a lens arranged within said sight-opening.

4. In a device of the class described, a closed casing having detachable end walls 105 and provided with a sight-opening, a squared shaft extending through the casing and en- gaging the end walls thereof, partitions ar- ranged within the casing and provided with squared openings for the reception of the 110 shaft and each provided with an opening in alinement with the sight-opening, a plu- rality of movable members mounted on the shaft between said partitions and provided with translucent portions of different de- 115 gree of opacity, said translucent portions and openings being adapted to be brought, respectively, into line with the sight-opening.

5. In a device of the class described, a closed casing having detachable end walls 120 and provided with a sight-opening, there be- ing a plurality of guide-slots formed in the side walls of said casing, a shaft extending through the casing and engaging the end walls thereof, stationary partitions mounted 125 on the shaft and each provided with an open- ing in alinement with the sight-opening, a plu- rality of members rotatably mounted on the shaft between the partitions and having translucent portions adapted to be brought 130

into line with the sight-opening, pins secured to the rotary members and engaging the guide slots for limiting the movement of said members in either direction when the openings or
5 translucent portions thereof are in alinement with the sight-opening, and a biconvex lens arranged within said sight-opening.

In testimony that I claim the foregoing as my own I have hereto affixed my signature in the presence of two witnesses.

JOHN TIMOTHY HODGES.
